SAMUEL A. BLAKE, OF MILFORD, CONNECTICUT.

Design No. 3,451, dated April 27, 1869.

DESIGN FOR A HAT, IN IMITATION OF STRAW-BRAID.

The Schedule referred to in these Letters Patent and making part of the same.

To all whom it may concern:

Be it known that I, SAMUEL A. BLAKE, of Milford, in the county of New Haven, and State of Connecticut, have invented a new Design for Hat, in Imitation of Straw-Braid; and I do hereby declare the following, when taken in connection with the accompanying drawing, and the letters of reference marked thereon, to be a full, clear, and exact description of the same, and which said drawing constitutes part of this specification, and represents a top view of the hat.

This invention relates to a design for a hat, made of any material in imitation of braid or straw.

The crown A is of a combination of imitation braid. The brim B is a plain braid, the band C and the edge D representing braid of a different construction, running around the crown at the intersection of the brim, and around the edge of the brim, as shown in the illustration.

Having fully described my invention, What I claim as new, and desire to secure by Letters Patent, is—

The herein-described and illustrated design for an imitation braid hat.

SAML. A. BLAKE.
